UNITED STATES PATENT OFFICE.

ALBERT S. KELLAM AND NORMAN F. NORVELL, OF RICHMOND, VIRGINIA.

VALVE.

1,352,900.

Specification of Letters Patent. Patented Sept. 14, 1920.

Application filed March 15, 1919. Serial No. 282,975.

To all whom it may concern:

Be it known that we, ALBERT S. KELLAM and NORMAN F. NORVELL, citizens of the United States, residing at Richmond, in the county of Henrico and State of Virginia, have invented certain new and useful Improvements in Valves, of which the following is a specification, reference being had to the accompanying drawings.

10 This invention relates to certain improvements in valves, and it is an object of the invention to provide a novel and improved device of this general character whereby the same can be readily and conveniently locked in such a manner as to materially reduce the possibility of the valve being operated by an unauthorized person.

15 A further object of the invention is to provide a novel and improved valve particularly designed to be interposed in a fuel line leading to the carburetor of an internal combustion engine, together with means whereby the same may be held against manipulation after the valve has been moved 20 into closed position.

25 The invention consists in the details of construction and in the combination and arrangement of the several parts of our improved valve whereby certain important 30 advantages are attained and the device rendered simpler, less expensive and otherwise more convenient and advantageous for use, as will be hereinafter more fully set forth.

35 The novel features of our invention will hereinafter be definitely claimed.

In order that our invention may be the better understood, we will now proceed to describe the same with reference to the accompanying drawings, wherein:

40 Figure 1 is a view in top plan of a valve constructed in accordance with an embodiment of our invention.

Fig. 2 is a view in top plan of the main body or casting with the lock removed.

45 Fig. 3 is a view, partly in vertical section and partly in elevation, of our improved lock as herein embodied.

50 Fig. 4 is a view, partly in vertical section and partly in elevation, of the device as herein disclosed with the line of section substantially at right angles to the line of section in Fig. 3.

55 Fig. 5 is a view in bottom plan of the valve proper as herein disclosed, and

Fig. 6 is a view in perspective of the spacing plate as herein included.

As disclosed in the accompanying drawings, B denotes an elongated body preferably cast of metal and with its longitudinal axis vertically disposed when the device is 60 in applied position. The lower portion 1 of the body B is transversely enlarged and preferably rectangular in plan, while the upper portion 2 of the body is cylindrical in form.

65 The portion 2 of the body B is provided with a longitudinally directed bore 3 in communication at its lower end with a longitudinally directed and slightly tapered valve seat 4 extending within the lower 70 portion 1 of the body, and snugly arranged within the valve seat 4 for turning movement is the valve plug 5.

75 The valve plug 5 has transversely disposed therethrough a port 6 adapted to register or align, when the plug 5 is in one position, with the opposed ports 7. In communication with one of the ports 7 is a pipe 8 or other suitable conduit leading from a source of fluid supply, while in communication with the second port 7 is a pipe 9 or other conduit leading to a suitable point of discharge.

80 Insertible within the bore 3 is a cylindrical lock L preferably of the well known pin tumbler type and radiating from the upper or outer end portion of the barrel 10 of said lock is a longitudinally disposed wing or vane 11 which snugly engages within a longitudinally disposed pocket or recess 12 85 formed in the wall of the bore 3 and which pocket or recess is open at its outer end so that the lock L may be readily applied. The wing or vane 12 holds the barrel 10 against rotary movement when applied 90 within the bore 3 so that the same will be held in a fixed position relative to the plug 5 so that the device in its entirety may be assembled with convenience and facility.

95 The outer or upper end portion of the barrel 10 is provided with a head 14 overlying the adjacent end of the body B and secured thereto by the screws 15 or the like. It is preferred that after the screws 15 have been applied that the same be brazed so that 100 the lock L will be held against removal from within the body B under general conditions.

105 16 denotes a rotatable member supported by and disposed through the barrel 10 and which is adapted to be operated in a conventional manner through the medium of the key K. The lower or inner end portion 110

of the rotatable member 16 is provided with a blade 17 engaged within the transverse slot 18 formed in the upper or outer end of the plug 5 so that said plug 5 will be caused 5 to rotate in unison with and in the same general direction as the member 16. The inner or opposite end of the plug 5 is provided with a recess 19 (Fig. 5) which is preferably segmental with the side walls thereof perpendicular 10 related. Extending within said recess 19 is a pin 20, preferably threaded through the body B, and which coacts with the walls of said recess 19 to limit the rotation of the plug 5 in either direction.

15 We also find it of advantage to loosely position upon the bottom or inner end of the valve seat 4 a plate 21 of desired thickness and which serves to prevent the plug 5 from becoming wedged or seating too tight within 20 said valve seat. In other words, the plate 21 operates to permit the plug 5 to be rotated with a minimum of frictional resistance. It is also to be understood that the plate can be readily removed so that the 25 plate applied may be of a thickness to fully meet the requirements of practice.

Our improved valve as herein disclosed is particularly adapted for use in connection with the pipe line leading from a source of 30 fuel supply to the carburetor of an internal combustion engine, and when the plug 5 has been moved into a closed position to prevent the flow of the fuel through the pipes or conduits 8 and 9, the key K is readily 35 movable, so that the possibility of the plug being returned to open position by an unauthorized person is substantially entirely eliminated.

From the foregoing description, it is 40 thought to be obvious that a valve constructed in accordance with our invention is par-

ticularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the 50 several parts herein shown in carrying out our invention in practice except as herein-after claimed.

We claim:

A device of the class described including 55 a body having a recess in a face thereof, said recess comprising a conical portion and surmounting cylindrical portion, the lower portion of the recess affording a valve seat, said body having ports in communication with 60 the valve seat, a conical valve plug rotatably mounted within the valve seat and provided with a transverse port adapted to register with the ports of the body, a lock extending within the outer end portion of the recess, 65 said lock including a barrel, said barrel and body having coacting means for holding the barrel against rotation within the recess, and a rotatable member arranged within the barrel and bearing against the inner extremity 70 of the barrel, said rotatable member directly engaging the adjacent conical end of the valve plug.

In testimony whereof we hereunto affix our signatures in the presence of two witnesses. 75

ALBERT S. KELLAM.
NORMAN F. NORVELL.
